UNITED STATES PATENT OFFICE

HARRY J. NICHOLS, OF WASHINGTON, DISTRICT OF COLUMBIA

METHOD AND APPARATUS FOR SYNCHRONIZING TWO OR MORE DISCONNECTED ELEMENTS

Application filed January 10, 1923. Serial No. 611,828.

This invention relates to the method of and apparatus for synchronizing two or more disconnected elements.

The method is particularly intended to be applied to the synchronization of two rotatable members employed at the sending and receiving stations respectively in the transmission of photographs by radio and in the following description the invention will be described with relation to such application although it is, of course, to be understood that without material modification the apparatus and method are applicable to other purposes.

In order that a clearer perception of the present invention and the objects sought to be accomplished thereby may be had, it is to be stated that in the transmission of photographs by radio, in one method now employed, it is necessary to synchronize the motor driving the rotary disc-prisms or equivalent devices used in transmitting the photographic signals with the motor which drives similar rotary disc-prisms by which the photographic signals are reproduced as photographs. Heretofore in order to accomplish this synchronization it has been the practice to connect the prism driving motors at the sending and receiving station to the same electrical circuit of uniform frequency, as for instance to the public utility power system, whereby the synchronization of the motors was effected. It is therefore one of the purposes of this invention to obviate the necessity of so connecting the motors and to have them independent as to source of power and synchronized by radio communication from the sending to the receiving station.

A further object of this invention is to provide a method and means for synchronizing both as to time and phase two or more mechanisms which are remotely situated from each other. The mechanisms which are to be synchronized may consist of revolving elements, oscillating elements, or others of definite periodicity.

A further object is to provide a simple and practical mechanism which will be either manually operated or automatic in its operation to positively and accurately synchronize

movements of two relatively remote and physically disconnected elements.

Other objects will be in part obvious and in part hereinafter pointed out in connection with the following description taken in connection with the accompanying sheets of drawings forming part of this disclosure and illustrating two of various modifications of apparatus in which

Figure 1 shows a schematic diagram of the "A" or sending station omitting the details of the radio sending equipment, which may be of any suitable type or construction.

Figure 2 is a similar diagram of the "B" or receiving station.

Figures 3 and 4 are diagrams illustrating the method of obtaining automatic synchronization by means of a light reactive device such as a selenium resistance plate.

The elements of the "A" or sending station are as follows: A rotating disc 1 carries a contact 2 which periodically makes contact with a contactor 3 thereby transmitting periodic electrical impulses to a sending set 4 which broadcasts a corresponding signal or wave impulse at any desired wave length or frequency.

The "B" or receiving station consists of the usual receiving set having an auxiliary circuit 5 connected with a source of radiant energy such as light emitting elements or lamps 6 so as to make visible the periodic signals received from station "A"; and the rotating disc 7 which it is desired to synchronize with disc 1 of station "A".

The rotating disc 7 should be made of opaque material and have near its periphery a sight hole 8 arranged to pass over the stationary indicating lamps 6. The indicating lamps can be arranged in any desired sequence and to cover any desired sector. In the illustration red, white, and green lamps are shown, the lamps being underneath the disc so as to be seen only when the sight hole is passing over the sector covered by each lamp.

The operation of this device is as follows: For each revolution of the disc 1 a brief signal is sent out from the sending station "A". These signals are received at the station "B" 100

and after suitable amplification appear simultaneously as flashes of light in the indicating lamps 6, the flashes therefore having the same frequency as the disc 1 has revolutions.

If the disc 7 is then regulated to rotate so that the sight hole 8 is just over the white lamp each time it flashes, the white light will be seen continuously or intermittently, depending on the frequency of the flashes, and the disc 7 will be rotating exactly at the same rate as the disc 1, or the speed of one disc is an exact multiple of the other. It is assumed that in practice the receiving station will know the approximate speed of rotation of the disc 1 at the sending station "A" and that the usual forms of tachometers may be used to accomplish the approximate synchronization of the discs, while the method herein described may be used to accomplish their exact synchronization.

If, after the discs are synchronized with the white light showing, the speed of the disc 1 increases, or the speed of the disc 7 decreases, the red sector will be gradually uncovered so that the white light will change to red. Conversely, if the speed of the disc 1 decreases or that of disc 7 increases, the green light will appear, thus indicating automatically the manner in which to regulate the speed of the disc 7 to synchronize it again with the disc 1.

It will be apparent that the same result may be accomplished by having one stationary indicating lamp and variously colored sectors in the disc 7. Also, various changes and additions might be made to regulate the speed of the disc 7 automatically to that of the disc 1, for example:

One method of obtaining automatic regulation of the speed of the disc 7 is shown diagrammatically in Figures 3 and 4. The rotating disc 7 instead of being furnished with a sight hole is provided with sectors *a*, *b*, and *c* (three being shown by way of illustration) of varying degrees of radiant energy transmitting capacities, the most translucent sector being away from the direction of motion. The sectors are located in the disc 7 so as to pass directly over a single source of radiant energy such as the lamp 10 similar to those shown in Figure 2. Opposite the indicating lamp 10 is a radiant energy or light re-active device *H* such as a selenium resistance plate or photo-electric cell so arranged as to receive light passing from the lamp 10 through the translucent sectors in the disc 7. A connecting beam or light link is thus set up, under certain conditions, between the light source 10 and the re-active device 11, the said link being controllable as herein-after set forth. The light re-active device 11 is part of the speed regulating or control circuit, such as the shunt field circuit of the disc driving motor 12, it being understood that the light reactive device may

control the driving motor in the manner shown, or by other suitable means as commonly practiced such as intermediary relays and the like.

The operation of the automatic regulator is as follows: The indicating lamp 10 will flash in synchronism with the disc 1 as previously described. If none of the translucent sectors of the disc 7 are opposite the light re-active device 11 when the light flashes, the connecting light link between the lamp 10 and the re-active device 11 is cut off by the disc 7, and the re-active device will receive no light, and consequently its resistance will be relatively high. This resistance in the shunt field of the motor 12 will speed up the motor thus correcting by increasing the speed of the disc 7 connected therewith and thereby bring the translucent sector (*a*) over the lamp 10 at the time the light flashes, to thus complete the light link to the re-active device 11. The sector (*a*) will transmit some light to the light re-active device 11 thereby decreasing the speed of the motor 12; eventually the disc 7 is brought to the desired speed when the sector (*b*) is over the indicating lamp at the time the light flashes, the motor being normally regulated to give this result. Should the motor now increase its speed to thus cause a departure from the desired synchronous relation, the sector (*c*) will then pass over the lamp 10 as it flashes, thereby transmitting more light to the light re-active device 11 and decreasing the speed of the motor 12. Thus, the connecting light link is varied or controlled by the disc 7 and/or the sectors (*a*), (*b*), and (*c*), such variation or control thereupon effecting a control of the rate of movement of the disc 7. Obviously, the disposition and number of sectors, of which three are shown by way of illustration, is such to initially establish the desired synchronous relation between the discs 1 and 7 and to thereafter maintain the disc 7 in synchronism with the disc 1, it being apparent that, as in the previous case, a change in speed of the disc 1 will produce a corresponding change in the disc 7.

It will be seen that the method described can therefore be applied in various ways to accomplish the automatic or manual synchronization of two rotating discs and the method can be applied to other periodic motions by suitable adaptation.

It is further seen that similar methods utilizing radiant energy in any form to secure cooperation of the control elements may readily be practiced by suitable apparatus following the method herein disclosed, and all such methods are broadly encompassed in the following claims.

What I claim is:

1. In apparatus of the class described, in combination, a sending station, a periodically moving element and means associated there-

- with for sending an electrical impulse during each period or cycle of movement, a receiving station having an associated circuit which is energized upon the reception of the impulse, a moving element at the receiving station, a source of radiant energy in said circuit, means to control the energy transmitted from the energy source in accordance with the departure of the second element from a synchronous phase relation with the first element, and means responsive to such control to synchronize the movement of said elements. 5
2. In apparatus of the class described, in combination, a sending station, a periodically moving element and means associated therewith for sending an electrical impulse during each period or cycle of movement, a receiving station having a lamp circuit which is energized upon the reception of the impulse, a moving element at the receiving station, a lamp in said lamp circuit adapted to be energized upon the reception of the impulse, means to control the light transmitted from the lamp in accordance with the departure of the second element from a synchronous phase relation with the first element, and means responsive to such control to synchronize the movement of said elements. 10
3. In apparatus of the class described, in combination, a sending station, a periodically moving element and means associated therewith for sending an electrical impulse during each period or cycle of movement, a receiving station having an associated circuit which is energized upon the reception of the impulse, a moving element at the receiving station, a source of radiant energy in said circuit, a radiant energy reactive device cooperating therewith, means to control the connecting energy link between the energy source and the energy reactive device in accordance with the departure of the second element from a synchronous phase relation with the first element, and means responsive to such control to synchronize the movement of said elements. 15
4. In apparatus of the class described, in combination, a sending station, a periodically moving element and means associated therewith for sending an electrical impulse during each period or cycle of movement, a receiving station having an associated circuit which is energized upon the reception of the impulse, a periodically moving element at the receiving station, a light emitting device in said circuit and responsive to the reception of the impulse, a light reactive device cooperating with the light emitting device, means to control the connecting light link between the light emitting device and the light reactive device in accordance with a departure of the second element from a synchronous phase relation with said first element, and means re- 20
- sponsive to such control to synchronize the movement of said elements. 5
5. In an apparatus of the character described, in combination, a sending station, a periodically moving element, and means associated therewith for sending an electrical impulse during each period or cycle of movement, a receiving station having an associated circuit which is responsive to the reception of the impulse, a moving element at the receiving station adapted to be moved synchronously with said first element, a light emitting means in said circuit, a light responsive means in operative relation thereto, means including said second element to vary the connecting light link between said light emitting and light responsive means in accordance with a departure of said second element from a synchronous relation with the first element, and means operative upon such variation to control the movement of said second element. 70
6. In apparatus of the class described, in combination, a sending station, a periodically moving element and means associated therewith for sending an electrical impulse during each period or cycle of movement, a receiving station having an associated circuit which is energized upon the reception of the impulse and a source of radiant energy therein, a moving element at the receiving station, means for imparting movement to said second element in substantial synchronism with said first named element, radiant energy responsive means cooperating with the source of radiant energy, means to control the energy link between the energy source and the energy responsive means in accordance with a departure of the second element from a synchronous phase relation with the first element, and means responsive to such control to increase or decrease automatically the rate of movement of said second element thereby to maintain the same in synchronism with the first element. 80
7. In an apparatus of the character described, in combination, a sending station, a periodically moving element associated with said sending station, means associated with said element and operative to transmit an electrical impulse from the sending station during each cycle of movement, a receiving station, a moving element adapted to be synchronized with said first moving element, a plurality of members of different light transmitting capacities associated with said second element, and means responsive to the reception of the impulse and including a light reactive device affected by said members to increase or decrease automatically the rate of movement of said second element. 90
8. In an apparatus of the character described, in combination, a sending station, a rotatable member associated therewith, means associated with the rotatable element and operative at a fixed phase position of 95
- 100
- 105
- 110
- 115
- 120
- 125
- 130

- the element to transmit a periodic electrical impulse at each revolution thereof, a receiving station including an associated circuit which is energized upon the reception of the impulse, a rotatable element to be synchronized with said first element, a light emitting device in said circuit, a light reactive device cooperating therewith, means to control the connecting light link between the light emitting device and the light reactive device in accordance with a departure of the second element from a synchronous phase relation with said first element, and means responsive to such control to increase or decrease automatically the rate of movement of the second element whereby synchronism thereof with the first element is obtained.
9. In an apparatus of the character described, in combination, a sending station, a rotatable element associated therewith, means associated with the element and operative at a fixed phase position of the element to send a periodic electrical impulse at each revolution thereof, a receiving station, including an associated circuit which is energized upon the reception of the impulse, a rotatable element to be synchronized with said first element, a light emitting device in the circuit, the second element being provided with a plurality of members of different light transmitting capacities, and means inclusive of a motor and a light reactive device in circuit therewith for increasing or decreasing the rate of rotation of said second element thereby to maintain the same in synchronism with the first member, the light reactive device being responsive to the light from the light emitting device passing thru said members to control the electrical conditions of the motor.
10. In apparatus of the character described, in combination, a periodically moving element, another periodically moving element whose rate of movement is to be synchronized with that of the first element, a source of radiant energy associated with the second element, a radiant energy reactive device operatively disposed to said source of energy and to said second element as to be responsive to the energy from said energy source, means to control such response in accordance with a departure of the second element from a synchronous relation with the first element, and means controlled by said energy reactive device for correcting the rate of movement of said second element, thereby to maintain such synchronous relation of the second element with the first element.
11. In apparatus of the character described, in combination, a periodically moving element, another periodically moving element whose rate of movement is to be synchronized with that of the first named element, driving means for the second element, a control circuit for said driving means, a

source of radiant energy associated with said second element, said second element being provided with means to control the transmission of radiant energy from the energy source therethru in accordance with a departure of said second element from the desired synchronous relation, and a radiant energy reactive device in said control circuit responsive to such transmitted energy and operative upon such response to correct the rate of movement of the driving means in accordance with such departure, thereby to maintain the synchronous relation of the second element with the first element.

12. The herein described method of synchronizing the periodicity of two disconnected relatively remote moving elements which consists in the steps of sending an electrical impulse during a period of movement of one of said elements, utilizing said impulse at a distance to control a radiant energy emitting member, directing the radiant energy emitted from said member to a radiant energy reactive device, varying the response of the radiant energy reactive device to the energy directed thereto in accordance with a departure of the element to be synchronized from a synchronous phase relation with the said first named element, and controlling the rate of movement of the element to be synchronized in accordance with such response.

13. The herein described method of synchronizing the periodicity of two disconnected relatively remote removing elements which consists in the steps of sending an electrical impulse during a period of movement of one of said elements, utilizing said impulse at a distance to control a radiant energy emitting device, directing the energy emitted thru members of different energy transmitting capacities, and controlling the rate of movement of the element to be synchronized in accordance with the radiant energy transmitted thru said members.

14. The herein described method of synchronizing two relatively remote moving elements which consists in the steps of sending an electrical impulse during each period or cycle of movement of one of said elements, utilizing said impulse at a distance to control a radiant energy emitting device, varying the transmission of energy from said emitting device in accordance with the rate of movement and phase position of the element to be synchronized, and controlling the rate of movement of said element to be synchronized thru such variation.

Signed at Washington this 9 day of January, 1923.

HARRY J. NICHOLS.

CERTIFICATE OF CORRECTION.

Patent No. 1,759,864.

Granted May 27, 1930, to

HARRY J. NICHOLS.

It is hereby certified that error appears in the printed specification of the above numbered patent requiring correction as follows: Page 2, line 53, for "H" read "11"; page 4, line 100, claim 13, for "removing" read "moving"; and that the said Letters Patent should be read with these corrections therein that the same may conform to the record of the case in the Patent Office.

Signed and sealed this 22nd day of July, A. D. 1930.
